(57) **CLAIM**

The ornamental design for a linear actuator, as shown and described.

DESCRIPTION

FIG. 1 is a perspective front end view of a linear actuator seen from the top;

FIG. 2 is a perspective rear end view thereof seen from the top;

FIG. 3 is a first side view thereof;

FIG. 4 is a second side view thereof;

FIG. 5 is a top view thereof;

FIG. 6 is a bottom view thereof;

FIG. 7 is a front end view thereof; and,

FIG. 8 is a rear end view thereof.
